US00D582266S

(12) **United States Design Patent**
Helms, Jr. et al.

(10) **Patent No.:** **US D582,266 S**
(45) **Date of Patent:** **** Dec. 9, 2008**

(54) **PACKAGE**

(75) Inventors: **Charles F. Helms, Jr.**, Florence, SC (US); **Clyde B. Gore**, Hartsville, SC (US); **Victor Allen Sisk**, Statesville, NC (US); **Dale Rodney Potts**, Statesville, NC (US)

(73) Assignee: **Sonoco Development, Inc.**, Hartsville, SC (US)

(**) Term: **14 Years**

(21) Appl. No.: **29/277,942**

(22) Filed: **Mar. 14, 2007**

(51) **LOC (8) Cl.** **09-03**

(52) **U.S. Cl.** **D9/430**

(58) **Field of Classification Search** D9/430-433, D9/414-418, 420-429, 560, 737, 756; D3/273, D3/302; 206/421, 454, 457, 775-778, 784, 206/822; 220/500, 523-529, 552, 555; 229/100, 229/103.3, 104-106, 108, 108.1, 109, 110, 229/112-116, 116.1, 116.2, 117.15, 120, 229/125.015, 132, 138, 155, 162.1, 162.6, 229/162.7, 182.1, 213, 214, 247, 406, 407, 229/902, 911, 922, 930, 942

See application file for complete search history.

(57) **CLAIM**

The ornamental design for a package, as shown and described.

DESCRIPTION

FIG. 1 is a top perspective view of a package according to the present invention;

FIG. 2 is a bottom perspective view thereof;

FIG. 3 is a top plan view thereof;

FIG. 4 is a bottom plan view thereof;

FIG. 5 is a front elevational view thereof, a rear, right side, and left side elevation views are the same;

FIG. 6 is a front and right side angled elevational view thereof, a front and left side angle, a rear and right side angled, and a rear and left side angled elevational views are the same;

FIG. 7 is a top perspective view thereof illustrating an environmental structure associated with the present invention; and,

FIG. 8 is a bottom perspective view thereof illustrating an environmental structure associated with the present invention.

The broken lines represent portions of the design that form no part of the claimed design. The broken lines in FIGS. 7 and 8 show a structure included to illustrate the design in an environment of use and forms no part of the claimed design.

1 Claim, 8 Drawing Sheets
